RACKET BAG

Joseph Pelavin, Brooklyn, and Frank Ioviero, Howard Beach, N.Y., assignors to Droutman Manufacturing Company, Inc., New York, N.Y., a corporation of New York

Filed Jan. 8, 1965, Ser. No. 83,355

Term of patent 14 years

(Cl. D87—5)

FIG. 1

FIG. 2

FIG. 3

FIG. 4

FIG. 5

FIG. 6

FIG. 1 is a top plan view of a racket bag showing our new design;

FIG. 2 is a side elevational view thereof;

FIG. 3 is an end view thereof;

FIG. 4 is a bottom plan view thereof;

FIG. 5 is a view similar to FIG. 2 showing the opposite side; and

FIG. 6 is a view similar to FIG. 3 showing the opposite end.

We claim:

The ornamental design for a racket bag, as shown.
